UNITED STATES PATENT OFFICE

159,279

KNIFE SHARPENER

Samuel Lieberman, Boston, Mass.

Application September 16, 1949, Serial No. 5,027

Term of patent 3½ years

(Cl. D37—1)

To all whom it may concern:

Be it known that I, Samuel Lieberman, a citizen of the United States, residing at Roxbury, Boston, Commonwealth of Massachusetts, have invented a new, original, and ornamental Design for Knife Sharpener, of which the following is a specification, reference being had to the accompanying drawing, forming a part hereof.

I claim:

The ornamental design for a knife sharpener, as shown.

SAMUEL LIEBERMAN.
